UNITED STATES PATENT OFFICE

WILLIAM H. ALLEN, OF DETROIT, MICHIGAN, ASSIGNOR TO LEATHER MAKERS PROCESS COMPANY, OF DETROIT, MICHIGAN, A CORPORATION OF MICHIGAN

PROCESS OF TREATING SKINS OR HIDES PREVIOUS TO TANNING

No Drawing.

Application filed July 2, 1928. Serial No. 280,050.

This invention relates to treatment of un-tanned skins and hides. One of the customary methods of disinfecting raw skins and hides is the standard method authorized by the U. S. Government involving the soaking of the hides either green (fresh), salted or dried in a solution containing common salt and hydrochloric acid. In using such a method, it has been found that after disinfection, the skins or hides contain most of the free hydrochloric acid and, upon washing, there is always produced more or less swelling of the hides due to more or less hydrolysis of the leather substance, which hydrolysis is quite detrimental to the quality of the leather produced from such hides. Even when the washing is omitted and the hides are placed in the usual aqueous solution of calcium sulphide and hydrate, the same action occurs.

Among the objects of the present invention therefore, is to overcome such objections and prevent or at least reduce to a substantially negligible amount, the hydrolysis caused by the presence of this free material.

Other objects will readily occur to those skilled in the art upon reference to the following description.

In carrying out the present process, the skins or hides are disinfected in the usual manner with the brine containing hydrochloric acid, but instead of removing the hides from the disinfection solution, and washing or proceeding in the usual manner, the acid of the disinfecting solution is neutralized while the hides are still therein, by the addition to such solution containing the hides, of sufficient lime or other alkali such as caustic soda or soda ash, to neutralize the free acid present.

In the addition of the lime or alkali, there is, of course, interaction between the lime and the acid brine and there is always formed, when lime is used, some calcium chloride due to the neutralization of the acid.

After the neutralizing step, therefore, the hides may be removed from the solution and washed to remove the salt, calcium chloride, and other reaction products and, in such

washing it is found that no hydrolysis occurs and therefore no swelling.

When the washing has been completed, the hides are then ready to go into the sulphide and lime liquors and upon tanning produce leather of better quality than when the neutralizing step has been omitted.

If it is not desired to send the skins directly into the tanning process or other use, the washing step may be omitted and the sterilized skins drained of the neutralized brine, salted and stored or shipped as the case may be.

Now having described the invention and the preferred form of embodiment thereof, it is to be understood that the said invention is to be limited not by the specific details herein set forth but only by the scope of the claims which follow.

I claim:

1. The process of treating skins or hides preparatory to tanning, which comprises disinfecting the said skins or hides by immersing them in a solution containing common salt and hydrochloric acid, then neutralizing the solution with the hides therein by the addition of sufficient alkaline material to neutralize the free acid, then removing the hides and washing to substantially eliminate the contained salts.

2. The process of treating skins or hides preparatory to tanning, which comprises disinfecting the said skins or hides by immersing them in a solution containing common salt and hydrochloric acid, then neutralizing the solution with the hides therein by the addition of sufficient hydrated lime to neutralize the free acid, then removing the hides and washing to substantially eliminate the contained salts.

3. In a treatment of skins or hides preparatory to tanning, disinfecting said skins or hides in a solution containing free hydrochloric acid, neutralizing the acid in the hides by the addition thereto of a suitable alkaline material and washing the soluble salts from the hides.

4. In a treatment of skins or hides preparatory to tanning, disinfecting said skins or hides in a solution containing free hydro-

chloric acid, neutralizing the acid in the hides by the addition thereto of lime and washing the soluble salts from the hides.

5. In a treatment of skins or hides preparatory to tanning, disinfecting said skins or hides in a solution containing free hydrochloric acid and neutralizing the acid in the hides by the addition thereto of a suitable alkaline material.

WILLIAM H. ALLEN.
